DESIGN FOR A TOILET BOTTLE

William L. Schultz, New York, N. Y.

Application June 17, 1938, Serial No. 77,896

Term of patent 14 years

To all whom it may concern:

Be it known that I, William L. Schultz, a citizen of the United States of America, residing at New York city, county of New York, Borough of Manhattan, and State of New York, have invented a new, original, and ornamental Design for a Toilet Bottle, of which the following is a specification, reference being had to the accompanying drawing, forming a part thereof.

I claim:

The ornamental design for a toilet bottle, as shown.

WILLIAM L. SCHULTZ.
